UNITED STATES PATENT OFFICE.

CHARLES A. EDWARDS AND CHARLES F. MESSEY, OF ZILLAH, WASHINGTON.

POWER WHEEL.

Application filed September 22, 1923. Serial No. 664,163.

To all whom it may concern:

Be it known that CHARLES A. EDWARDS and CHARLES F. MESSEY, citizens of the United States, residing at Zillah, in the county of Yakima and State of Washington, have invented new and useful Improvements in Power Wheels, of which the following is a specification.

The present invention has for its purpose the provision of a device of this kind wherein the construction of the wheel includes a hollow drum tapered from its center to the opposite ends, with blades mounted thereon to be used as propeller blades or as fan blades for cooling purposes, or operated by a current of water when the drum is submerged in a stream and in conjunction with a balance wheel on the interior of the drum to insure momentum to the drum when rotating.

Power wheels have heretofore been devised but which have various disadvantages due to the same being retarded in operation on account of rocks and trash and for the reason that such wheels are, as a rule, partially submerged in the water. Obviously, as the tide varies, the partial submersion of the wheel likewise varies. A low tide of water will have no effect upon the wheel. Furthermore, it is obvious that the present construction of power wheel may be used as a propeller on a ship.

Also power wheels heretofore used have the blades too close together which will not permit the water to have the desired effect thereon in order to insure a maximum power. Also in those wheels which are only partially submerged, the weight and the power of the undercurrent of the water is lost, whereas by the use of the present wheel, due to the same being entirely submerged, such lost power is gained.

Another purpose is to provide a power wheel wherein the blades are removable from the drum which is also capable of being removed from its supporting shaft which will permit the power wheel to be easily and very cheaply transported. For instance, the present wheel may be shipped practically in a collapsible condition and disassembled and packed in small compass, enabling the wheel to be easily handled during its transportation.

Also floating trash or floating timber from timbered streams will interfere considerably with the operation of those power

wheels which are partially submerged whereas, due to the present construction of wheel being entirely submerged, the floating trash and timber passes over the wheel and entirely avoids this trouble.

Still another purpose is to provide a power wheel wherein the blades are mounted upon the drum detachably with suitable bolts or the like, the heads being countersunk to prevent trash and the like from entangling therewith. This manner of mounting the blades also permits them to be easily removed for shipment of the wheel.

A further purpose is the provision of a plurality of blades including reinforcing braces in order to insure that the blades will withstand the strain of water thereon.

It is to be understood that the particulars herein given are in no way limitative and that, while still keeping within the scope of the invention, any desired modifications of detail and desired proportions may be made in the apparatus according to the circumstances.

The invention comprises further features and combinations of parts to be hereinafter set forth, shown in the drawings and claimed.

In the drawings:

Figure 1 is a view in elevation of a power wheel constructed in accordance with the invention and showing the same entirely submerged in a stream of water.

Figure 2 is a longitudinal sectional view showing the interior construction of the drum and the mounting of the blades.

Figure 3 is a sectional view on line 3—3 of Figure 1, showing how one of the blades is fastened to the drum by means of the countersunk bolts and also illustrating the brace for the blade.

Figure 4 is a detail view in perspective of one of the blades.

Figure 5 is a detail view on line 5—5 of Figure 1, showing more clearly the angle plates and also the abruptness of the ends of the blades.

Referring to the drawings, 1 designates a suitable reinforced stone, concrete or cement structure which rises from the bed of the stream. This structure may be a combination of stone, cement and concrete. Suitable bearings 2 are mounted upon the end supports 3 of the stone or cement structure and, if found convenient, these bearings may be housed, the housings to contain suit-

able lubrication to prevent corrosion of the metal parts and to permit the wheel to freely rotate. Such housings (not shown) may be of a conventional form and so constructed as to preclude the water.

Journalled in the bearings 2 is a shaft 4 on which the drum 5 is mounted, the opposite ends of the drum being keyed to rotate with the shaft, as at 6. It is the aim to construct this drum water-tight and disposed upon the interior of the drum centrally thereof is a balance wheel 7 which insures momentum to the drum when in action.

The drum comprises a body of elongated form having a central enlarged portion of substantial diameter with opposite end portions of equal length, said end portions being conical from the central enlarged portion to the remote terminals of the drum. A plurality of blades 8 are mounted on the drum and are relatively curved transversely. The greater portion of each blade is outstanding from the drum and has a right angle edge flange 9 conforming spirally with and secured to one of said conical end portions by means of bolts 9^a. The heads of the bolts 9 are countersunk to prevent trash and the like from entangling therewith. The inner edge of the remaining portion of each blade is bent over the central enlarged portion of the drum and conforms spirally with decreased pitch over the leading spiral to a relatively short part of the opposite conical end portion, thereby disposing the remaining part of the curved blade spirally and more abruptly. However, the blades may be otherwise disposed if found practicable, though they are curved in order to insure the proper impinging of the water, so as to insure propulsion of the drum and the shaft on which it is mounted. As previously stated, the remaining or lesser portion of each blade conforms spirally to a relatively short part of the opposite end portion of the drum and is fastened to an outstanding flange 10 of an angle plate 11 secured to the drum.

Suitable reinforcing braces of curved contour to conform to the curvature and the disposition of a blade are disposed upon the drum. These reinforcing braces 13 are also secured to the wall of the drum by bolts 14 which have their heads countersunk obviously for the purpose of preventing trash entangling therewith. One of the braces is carried by the conical portion of the drum

and is bent in a suitable manner, as at 15, to permit this reinforcing brace to conform to the curvature of the blade. Also where the braces are secured to the blade, the securing bolts 16 thereof are countersunk to also prevent the trash from entangling therewith. The other brace of each blade overlies the outstanding flange of the angle plate and is secured by a bolt 17. The head and nut of this bolt are also countersunk.

The blades are curved as shown to permit the water to impinge thereagainst to insure imparting a revoluble movement to the drum. Obviously, by rotating the drum or, in other words, belting power to the shaft, the drum may be rotated so that the blades may churn the air, enabling the wheel to be used for cooling purposes. Also when the power is applied to the shaft, the wheel may be used as a propeller for use on various ships.

The invention having been set forth, what is claimed is:

A water-propelled wheel comprising a drum of elongated form having a central enlarged portion of substantial diameter, with opposite end portions of equal lengths, said end portions being conical from the central enlarged portion to the remote terminals of the drum; a plurality of blades on the drum and being relatively curved transversely; the greater portion of each blade being outstanding from the drum, and having a right angle edge flange conforming spirally with and secured to one of said conical end portions; the inner edge of the remaining portion of each blade being bent over the central enlarged portion, and conforming spirally with decreased pitch over the leading spiral to a relatively short part of the opposite end portion, thereby disposing the remaining part of the curved blades spirally and more abruptly, whereby to offer increased resistance to the water and increase the power of the wheel; a pair of braces secured to the drum; and an angle plate secured to said relatively short part of the drum, said angle plate having one of its flanges fastened to and between the blade and certain of the braces, thereby withstanding the water pressure due to the increased resistance.

In testimony whereof they affix their signatures.

CHARLES A. EDWARDS.
CHARLES F. MESSER.
